UNITED STATES PATENT OFFICE

JOHN L. ERISMAN, OF OAK PARK, ILLINOIS, ASSIGNOR TO LINK-BELT COMPANY, OF CHICAGO, ILLINOIS, A CORPORATION OF ILLINOIS

SPEED-REDUCTION UNIT

Application filed October 14, 1926. Serial No. 141,466.

This invention relates to a speed reduction unit and to a housing therefor. In the form illustrated it is particularly adapted for use in driving screw conveyors. It is not limited to this use, however, and it has for one object to provide a compact housing which will support the reduction gearing and driving motor and a portion of the conveyor element. Another object is to provide in connection with such a mechanism the features of ready accessibility and inspection. Other objects will appear from time to time throughout the specification and claims.

My invention is illustrated more or less diagrammatically in the accompanying drawings, wherein:

Figure 1 is a side elevation;

Figure 2 is an end elevation with parts in section;

Figure 3 is a horizontal section taken on line 3—3 of Fig. 1;

Figure 4 is a generally horizontal section taken on line 4—4 of Figure 2;

Figure 5 is a detail in vertical section showing the belt tensioning mechanism;

Figure 6 is a modified form with parts in elevation and parts in section;

Figure 7 is a section taken on line 7—7 of Figure 6, showing the parts in elevation;

Figure 8 is a generally horizontal section taken on line 8—8 of Figure 6;

Figure 9 is a generally horizontal section taken on line 9—9 of Figure 6.

Like parts are indicated by like characters throughout.

A is a foundation upon which the speed reduction unit and its housing is mounted and to which it is normally fastened by screws or bolts A¹. Any other type of foundation might be substituted.

The speed reduction housing is formed of two halves B and C which are normally bolted together. The half B is provided with a laterally extending bottom or base portion B¹ and it is this portion which is bolted to the foundation. The portion B has formed, preferably integrally with it, a relatively short portion B² within which a bushing B³ is positioned. This serves as a bearing for one end of one of the shafts. B⁴ is a flat boss formed

in the member B and provided with a bushing B⁵.

The portion C is provided with a laterally extending base portion C¹, an integral boss C², which includes a bushing C³, and a second integral boss C⁴ which encloses a bushing C⁵.

The two parts B and C of the housing are removably attached together by means of bolts D, and they are provided with generally flat laterally extended upper surface portions B⁶ and C⁶ respectively, which are provided with threaded perforations.

E is a movable motor carrying plate provided with slots E¹ E¹, and a downwardly bent edge E². E³ is a cavity formed partially in the member B and partially in the member C. E⁴ is a bolt which has its head E⁵ located in such cavity and extends through a perforation in the downwardly bent portion E² of the plate E. E⁶ is a nut on the bolt.

F is a driving motor bolted to the plate E by means of bolts F¹. The position of the motor on the top of the gear housing may be varied by sliding the plate, and this may be done by manipulating the bolt E⁴. When the plate has been moved to the proper position, the screws E⁷ are tightened and the plate is thus held in position. This is carried out in order to secure proper initial adjustment of the motor and in order to secure re-adjustment of the parts when that becomes necessary.

G is a shaft having its one end supported in a bearing B⁴ and its other end in a bearing C⁴. It is keyed on to a large gear G¹. G² is a motor shaft having keyed on it a pinion G³. G⁴ is a driving chain preferably of the "silent chain" type, extending about the pinion G³ and the gear G¹. By means of this chain the gear G¹ is driven from the motor. G⁵ is a removable housing enclosing the gear and pinion and the chain.

H is a shaft having one end supported in a bearing B² and being supported intermediate its ends in the bearing C². As here shown it has fitted over it and fastened to it the hollow shaft H¹ of the conveyor about which is fastened the helical conveying portion H². H³ is an enclosing housing in which the conveyor is positioned. H⁴ is a gear fas-

tened on the shaft H and meshing with a pinion I fastened on the shaft G. By means of this pinion and gear, the shaft H and the conveyor which is attached to it are driven from the motor and a double speed reduction is provided.

In Figures 6, 7, 8, and 9 a modified form of the invention is shown. This form differs from that above described particularly in the fact that the housing for the reduction elements is split horizontally instead of vertically.

J is the lower section of the housing provided with lateral extensions J¹ which are fastened to the foundation by the above mentioned screws A¹. This housing has formed in it halves of bearings J² J² and J³ J³. It has formed within it the cavity J⁴ in which a portion of the gearing is positioned.

K is the upper half of the housing. It is provided adjacent its top with lateral extensions K¹, and it has formed in its halves of bearings corresponding to the bearings J² J³, adapted to be joined to them to form complete bearings for the shafts of the speed reduction gearing which will be described below. An opening K² is provided in the housing K and it is provided with a removable cover K³ by means of which the interior of the entire housing may be inspected.

L is a motor carrying plate similar to the plate E described above. It is provided with slots L¹ L¹ and carries a motor M which is fastened to it by means of screws M¹ M¹. It has a downwardly bent portion L² within which is removably positioned a set screw L³ by means of which it may be moved. L⁴ L⁴ are screws or bolts by means of which the plate L is held in position after it has been properly adjusted on top of the housing.

N is a motor shaft carrying a pinion N¹. O is a stub shaft mounted in the bearings J², carrying the gear O¹ and the pinion O². O³ is a chain passing about the pinion N¹ and the gear O¹ by means of which the gear is driven from the motor. O⁴ is a housing enclosing the pinion and the gear and the chain.

P is a shaft mounted in bearings J³ and carrying a gear P¹ which meshes with the pinion O² on the shaft O. This shaft may extend laterally from the housing and may carry any type of power take-off, and any mechanism which it is desired to operate through the gearing above described.

Although I have shown an operative device, still it will be obvious that many changes might be made in size, shape, and arrangements of parts without departing materially from the spirit of my invention; and I wish, therefore, that my showing be taken as in a sense diagrammatic.

I claim:

1. In combination in a gear reduction assembly, double reduction elements, including a driving motor, a shaft, and a driven shaft,

the driving motor carrying a pinion, the first mentioned shaft carrying a gear driven from such pinion and carrying also a second pinion, the driven shaft carrying a gear driven from such second pinion, and a housing enclosing the second pinion and driven gear and having formed within it bearings for the shaft and the driven shaft and serving as a support for the driving motor, adjustable means whereby the same is mounted upon such housing, the housing being formed in two main portions, means for joining them together, such means including a motor carrying element, the same being adjustably mounted on the housing.

2. In combination in a gear reduction assembly, double reduction elements, including a driving motor, a shaft, and a driven shaft, the driving motor carrying a pinion, the first mentioned shaft carrying a gear driven from such pinion and carrying also a second pinion, the driven shaft carrying a gear driven from such second pinion, and a housing enclosing the second pinion and driven gear and having formed within it bearings for the shaft and the driven shaft and serving as a support for the driving motor, adjustable means whereby the same is mounted upon such housing, the housing being formed in two main portions, means for joining them together, such means including a motor carrying element, the same being adjustably mounted on the housing, and an additional removable housing enclosing the driving motor pinion and the first mentioned gear.

Signed at Chicago, County of Cook and State of Illinois, this 27th day of September, 1926.

JOHN L. ERISMAN.
